No. 630,018.

Patented Aug. 1, 1899.

J. M. WILSON,

SYRUP PITCHER.

(Application filed Dec. 31, 1898.)

(No Model.)

THE NORRIS PETERS CO., PHOTO-LITHO., WASHINGTON, D. C.

UNITED STATES PATENT OFFICE.

JOHN M. WILSON, OF WOODLAWN PARK, COLORADO.

SYRUP-PITCHER.

SPECIFICATION forming part of Letters Patent No. 630,018, dated August 1, 1899.

Application filed December 31, 1898. Serial No. 700,844. (No model.)

To all whom it may concern:

Be it known that I, JOHN M. WILSON, a citizen of the United States, residing at Woodlawn Park, in the county of El Paso and 5 State of Colorado, have invented a new and useful Syrup-Pitcher, of which the following is a specification.

The invention relates to improvements in syrup-pitchers.

10 The object of the present invention is to improve the construction of syrup-pitchers and to provide a simple, inexpensive, and efficient one adapted to shut off effectively the flow of the syrup and to catch the drippings and 15 conduct the same back to the interior of the pitcher, and thereby prevent syrup from accumulating on the exterior of the same.

A further object of the invention is to enable the passages for conducting the syrup 20 back to the pitcher to be readily cleaned and to provide simple and efficient means for holding the pitcher open while it is being supplied with syrup.

The invention consists in the construction 25 and novel combination of parts hereinafter fully described, illustrated in the accompanying drawings, and pointed out in the claims hereto appended.

In the drawings, Figure 1 is a perspective 30 view of a syrup-pitcher constructed in accordance with this invention. Fig. 2 is a vertical sectional view of the same. Fig. 3 is a detail perspective view of the removable conical sleeve. Fig. 4 is a detail perspective view 35 of the upper portion of the pitcher, the lid and the sleeve being removed. Fig. 5 is a horizontal sectional view on line 5 of Fig. 2.

Like numerals of reference designate corresponding parts in all the figures of the drawings.

1 designates a pitcher provided at its neck with inner and outer cylindrical sleeves 2 and 3, spaced apart to provide a lower annular recess to receive the upper edges of the body 45 portion of the pitcher and connected by a ring 4, disposed at an inclination and forming inclined passages for conducting the drippings back into the pitcher. The ring 4 has its front portion located adjacent to the upper edge of 50 the inner sleeve 2, and the latter is provided at its back with a recess or opening 5, forming a communication between the pitcher and

the inclined passages. The front of the outer sleeve is cut away at 6 to provide an entrance to the passages 7, and within the sleeve 3 is 55 fitted a removable tapering or conical sleeve 8, which forms a mouth for the pitcher. The removable sleeve 8 flares upwardly, its lower reduced end fitting around the upper end of the inner stationary sleeve 2.

60 The outer stationary sleeve or ferrule is provided at its back with three hooks 9, which engage over the upper edge of the removable sleeve 8, and the latter is provided with V-shaped notches 10, adapted to be brought into 65 register with the hooks 9 to permit the tapering sleeve to be removed and replaced for affording access to the passages 7, so that the latter may be conveniently cleaned. The hooks 9, which engage the sleeve 8, are formed 70 integral with the outer sleeve or ferrule 3, and consist of tapering tongues bent inward, as shown, and the sleeve 8 is interlocked with the same by partially rotating it.

The pitcher is provided at the back of the 75 sleeve 3 with a support 11, consisting of a horizontal flange and upwardly-projecting perforated ears 12, receiving a pintle 13, which hinges a lid 14 and a lever 15 to the outer sleeve. The lid or cover 14 is provided with 80 a shank or handle 16, having perforated ears 17 for the reception of the pintle and provided at its ends with a loop 18, adapted to be engaged by a hook 19, which is mounted on the outer sleeve, at the back thereof, for 85 holding the lid or cover open while the said pitcher is being filled. The lid is held normally closed by a spring 20, disposed on the pintle and engaging the support and the shank or handle 16.

90 The lever 15 is provided at its handle end with an opening 21 of sufficient size to permit the handle of the lid to swing through it, and the said lever is provided at opposite sides of the opening with depending ears 22, 95 located at the outer faces of the ears of the support. Both the cover and the lever are adapted to be operated simultaneously, and the latter is provided at a point above the center of the lid or cover with laterally-disposed arms 23, curving downward and forming, with the front end of the lever, a support for a curved shield 24, arranged to cover the recess or cut-away portion of the sleeve or fer-

rule 3. The shield is curved and its lower edge 25 is bent inward, as shown, and the sleeve or ferrule 3 is provided at the bottom of its cut-away portion with an inwardly-extending flange 26, formed by bending the edge of the cut-away portion inward.

Both of the hinged members are simultaneously opened and the lid is closed first to cut off the flow of the syrup, and after the flow has stopped the shield is closed over the cut-away portion and any syrup remaining on the lip of the pitcher will flow into the passages 7 and be returned to the pitcher.

The invention has the following advantages: The pitcher, which is simple and comparatively inexpensive in construction, is adapted to prevent syrup from accumulating on its exterior and it will conduct all drippings back into it. The lid or cover is adapted to be closed to shut off the supply, and the shield covers the cut-away portion or recess which forms an entrance to the passages 7. The flaring sleeve which forms the mouth or lip of the pitcher is detachably interlocked with the same and may be readily removed when it is desired to clean the passages 7.

Changes in the form, proportion, and minor details of construction may be resorted to without departing from the spirit or sacrificing any of the advantages of this invention.

What is claimed is—

1. In a device of the class described, the combination of a body having a return for the drip, a hinged lid having a handle, and a lever provided with a shield and fulcrumed between its ends, said lever being provided at its back with an opening of sufficient size to permit the handle of the lid to swing through it, substantially as described.

2. In a device of the class described, the combination of the inner and outer stationary sleeves spaced apart to form a passage, the inner sleeve being provided with a recess, and a removable sleeve mounted upon the inner sleeve and located above the bottom of the said recess, substantially as described.

3. In a device of the class described, the

combination of a body having a lip and provided with passages arranged outside of the same, a lid hinged to the body and having a handle, a lever fulcrumed between its ends and provided at its back with an opening to receive the handle of the lid, and having arms located in advance of the hinged joint, and a curved shield supported by the arms and the front end of the lever and arranged to cover the entrance to the said passage, substantially as described.

4. In a device of the class described, the combination with the body of a pitcher provided at its upper edge with hooks, of a removable lip interlocked with the hooks and provided with recesses adapted to register with the same to permit the lip to be engaged with and disengaged therefrom, substantially as described.

5. In a device of the class described, the combination of the inner and outer stationary sleeves spaced apart, the inner sleeve being provided with a recess, an inclined ring interposed between the two and forming the bottom of passages extending to the said recess, a removable sleeve interlocked with the outer stationary sleeve, a lid arranged to close over the removable sleeve, and means for closing the passages, substantially as described.

6. In a device of the class described, the combination of the outer sleeve cut away at its front, an inner stationary sleeve provided at its back with an opening and spaced from the outer sleeve to form a passage, a lip removably mounted within the outer sleeve, a cover arranged to close on the lip, and a shield arranged to cover the cut-away portion of the outer sleeve, substantially as described.

In testimony that I claim the foregoing as my own I have hereto affixed my signature in the presence of two witnesses.

JOHN M. WILSON.
